UNITED STATES PATENT OFFICE.

HENRY PUFF, OF ST. CLOUD, MINNESOTA.

CAMPING OUTFIT.

1,332,635.

Specification of Letters Patent.

Patented Mar. 2, 1920.

Application filed August 6, 1919. Serial No. 315,717.

To all whom it may concern:

Be it known that I, HENRY PUFF, a citizen of the United States, residing at St. Cloud, in the county of Stearns and State 5 of Minnesota, have invented certain new and useful Improvements in Camping Outfits, of which the following is a specification, reference being had to the accompanying drawings.

10 This invention relates to an improved camping outfit, which may be used by camping out parties, either those on foot or those traveling in vehicles, such as automobiles and the like.

15 In fact, a most important object of the invention is the provision of a camping outfit, which includes a table, opposite seats or benches, in combination with means connecting the seats or benches and the table, 20 whereby a rigid structure may be provided.

The invention further aims to provide a table top comprising a pair of sections hingedly united, and which have marginal flanges and also provided with compartments, not only to receive table utensils, but also to receive condiment receptacles, and also a compartment for the reception of the braces or connections between the seats or benches and the table top, whereby the various parts may be arranged in a small 30 compass.

The invention further aims to provide a table top, and a pair of seat or bench sections, which, when the sections of the table 35 top are folded, the seat or bench sections are adapted to cover the compartments to hold the various articles in place, and to hold the sections of the table top folded, so that the entire camping outfit may be arranged in a small compass, so that it can be conveniently carried in an automobile or on the running board thereof.

A further object of the invention is the provision of a collapsible or foldable camping outfit, including means whereby the bench or seat sections may be clamped together, with the table top sections folded, and interposed between the bench or seat sections.

50 A further object of the invention is the provision of improved legs for the support of the bench or seat sections, in combination

with means for holding the legs either folded or extended.

A further object of the invention is the 55 provision of marginal sheet metal flanges carried by the bench or seat sections, to overlap each other, and to overlie the table top sections when folded, to render the camping outfit dust and rain proof, as well as 60 concealing the table top sections when folded.

The invention further aims to provide a camping outfit, which is simple, efficient and practical in construction, and may be manufactured for relatively low cost and sold at a reasonable profit, and moreover, to provide a device which may be used as a card table or the like.

While the design and construction at 70 present illustrated and set forth are deemed preferable, it is obvious that as a result of a reduction of the invention to a more practical form for commercial purposes, the invention may be susceptible to changes, and 75 the right to these changes is claimed, provided they are comprehended within the scope of what is claimed.

The invention comprises further features and combination of parts, as will be herein-after set forth, shown in the drawings and claimed.

In the drawings:

Figure 1 is a view in perspective of the improved camping outfit folded, and as applied to the running board of an automobile.

Fig. 2 is a perspective view of the improved camping outfit opened up and the parts arranged in position ready for use.

Fig. 3 is a bottom plan view of Fig. 2, 90 showing the supporting legs folded against the under faces of the seat or bench sections.

Fig. 4 is a detail sectional view on line 4—4 of Fig. 2.

Fig. 5 is a sectional view on line 5—5 of Fig. 2, showing the braces between the table top sections and the seat or bench sections, and showing the connections for the braces, and also illustrating the braces between the 100 bench or seat sections to render them more rigid with relation to the table.

Referring more especially to the drawings, 1 and 2 designate the table top sec-

tions of a table and which are hingedly connected at 3. The table top sections comprise the elongated table top pieces 4, which are provided with marginal flanges 5, and arranged between the longitudinal flanges of the table top sections are partitions 6 and 7, thereby dividing the table top sections into several compartments 8, 9, 10, 11, 12 and 13. The compartment 9 is sub-divided by means 10 of the partitions 14, thereby constructing a plurality of compartments 15, one of which is designed to receive a table cloth (not shown), another to receive condiment receptacles or the like (not shown), while 15 the others are adapted to receive knives, forks and spoons or other similar table articles.

The flanges of the two table top sections, particularly their parts near the ends of the 20 table top sections, are provided with transverse grooves 16, there being sheet metal plates 17 countersunk in the end parts of the flanges and secured in place as indicated at 18, thereby covering the grooves as shown.

25 When the table top sections are folded, the table top pieces 4 contact, and in order to cover the compartments of the table top sections, additional sections 19 are provided. These sections 19 are longer than the table 30 top sections and are not only used as cover sections, but also as bench or seat sections. When the sections 19 are utilized as benches or seats, they are arranged on opposite longitudinal sides of the table top, there being 35 braces 20 between the seat or bench sections and the table top, to reinforce the seats or benches relative to the table. These braces 20 are in the form of iron bars which have elongated bent parts or portions 21 and 22 40 to enter the channels or grooves of the end portions of the marginal flanges 5 of the table top sections. In fact, the bent portions 21 and 22 engage in the grooves 16 under the plates 17, and furthermore, the bent portions 21 are long enough to extend across the 45 joint between the table top sections, thereby preventing accidental collapsing of the sections when they are used to form a table.

Secured on the adjacent edges of the seat 50 or bench sections are arched straps 23. In fact, the arches of the straps 23 are arranged coincident to the recesses or notches 24 of the adjacent edges of the seat or bench sections. The braces 20 are provided with 55 angularly protruding extensions 25, engaging between the arches and the notches, thereby connecting the braces securely in position and reinforcing the table top relatively to the seat or bench sections.

60 Metal straps 26 are secured to the under faces of the seat or bench sections and are provided with bearings 27 for the reception of the supporting legs 28. Each supporting leg consists of a single piece of rod material bent to provide ground engaging por-

tions 29 and bearing engaging portions 30, which are mounted in the bearings 27. The rod material of each leg is also bent to form the loop part 31. In forming each supporting leg the rod material has its ends secured 70 together in any suitable manner, preferably by brazing or welding, or in any other suitable manner as indicated at 32, so that the rod material of the leg is endless. The legs may be folded against the under faces of the 75 seat or bench sections, or arranged to depend from the seat or bench sections, so that their parts 29 may engage the ground or any other suitable support. Suitable leaf spring arms 33 are secured as at 34 to the under 80 faces of the seat or bench sections, and are adapted to lie flat against the sections. The free ends of the leaf spring arms are bent to form the U parts 35, which, when the legs depend from the seat or bench sections, are 85 designed to engage the transverse parts of the loops 31, thereby reinforcing or bracing the legs, so as to support the seat or bench sections. However, when the legs are folded flat against the under surfaces of the seat 90 or bench sections, the leaf spring arms 33 overlie the loops 31, thereby holding the legs folded. Also, when the parts of the camping outfit are folded or collapsed, the seat or bench sections 19 are disposed to cover 95 the compartments of the table top sections, and in this case the supporting legs 28 will enter the compartments 8, 10, 11 and 13, so that the seat or bench sections may be engaged flat against the edges of the marginal 100 flanges of the table top sections.

The under faces of the seat or bench sections 19 adjacent their ends are provided with cleats 36, which overlie the ends of the table top sections and contact with each 105 other, thereby making a tight closing fit between the parts.

Sheet metal angle pieces are secured to the seat or bench sections as shown at 37, and the marginal flanges of these sheet 110 metal pieces 38 overlap each other, that is, when the seat or bench sections are disposed in contact with the flanges of the table top sections. Furthermore, the flanges of the sheet metal pieces 38 overlie the marginal 115 flanges of the table top sections, thereby not only rendering the camping outfit dust and rain proof, but also housing the table top sections. When the parts of the camping outfit are folded or collapsed, suitable bolts 39 120 are passed transversely through the cleats 36, and through the seat or bench sections, and are provided with wing nuts 40, to clamp the various parts securely together, thereby holding the outfit in a small compass so as to be conveniently carried in an automobile. If necessary, the bolts 39 may be passed upwardly through the running board of the automobile, as well as through the cleats and the seat or bench sections, so 125 130

as to fasten the outfit in place, so that it can be very conveniently carried.

Pivoted as at 41 to the outer face of one of the seat or bench sections near its opposite ends are the brace rods 42. These rods 42 have right angle extended ends 43 to enter sockets 44 of the opposite seat or bench section, so as to reinforce the seat or bench sections relatively to each other, that is, when 10 the various parts of the outfit are arranged as shown in Fig. 2.

When the various parts of the camping outfit are collapsed or folded, the braces 20 are arranged in the compartment 12, and 15 are held therein by suitable holding members 45 and 46.

In order to reinforce the loops 31, and at the same time render the legs more rigid braces 60 extend from the opposite sides of 20 the legs, and are secured to the opposite portions of the legs in any suitable manner as indicated at 61. For instance, the securing of the braces may be accomplished by brazing or riveting, preferably the former. 25 Furthermore, the braces 60 are brazed or otherwise secured to the loops 31, thereby insuring strength and rigidity.

The invention having been set forth, what is claimed as new and useful is:

30 1. In a camping outfit, the combination with hingedly united table top sections and seat or bench sections arranged upon opposite sides of the table top sections below and in parallel therewith, of means extending 35 across the hinged edges of the table top sections to reinforce them, said means having braces detachably connecting with the seat or bench sections, and braces connecting the seat or bench sections.

40 2. In a collapsible camping outfit, the combination with foldable table top sections having their edges hingedly united, of opposite seat or bench sections below and in parallel with the table top sections and provided with collapsible supporting legs, means 45 extending across the hinged edges of the table top section to reinforce them, said means having braces detachably connecting with the seat or bench sections, and transverse braces connecting the seat or bench sections.

50 3. In a collapsible camping outfit, the combination with table top sections having the edges hingedly united and provided with 55 compartments and being foldable whereby the compartments face outwardly, of seat or bench sections adapted, when collapsed, to cover the compartments of the table top sections, said seat or bench sections having foldable legs adapted to support the seat or bench sections upon opposite sides of the table top sections below and in parallel therewith, and also adapted, when folded, to position in certain of the compartments of 60 the table top sections, and means extending 65

across the hinged edges of the table top sections to reinforce them, said means having braces detachably connecting with the seat or bench sections, when the latter sections are so used.

70 4. In a collapsible camping outfit, the combination with table top sections, of seat or bench sections having foldable legs, braces detachably connecting between the table top sections and the seat or bench sections, said table top sections being hingedly united whereby they may be folded, certain of said braces having means extending across the hinged edges of the table top sections, thereby reinforcing them.

75 5. In a collapsible camping outfit, the combination with a pair of table top sections having compartments, means for hingedly uniting said sections, whereby they may be folded with the compartments facing outwardly, of seat or bench sections having supporting legs, and adapted, when the seat or bench sections are collapsed, to cover the compartments of the table top sections, braces detachably connecting between the 80 latter sections and the table top sections, and means integrally connecting said braces and overlying the hinged joint of the table top sections.

85 6. In a collapsible camping outfit, the combination with a pair of table top sections having compartments, means for hingedly uniting said sections, whereby they may be folded with the compartments facing outwardly, of seat or bench sections having 90 supporting legs, and adapted, when the seat or bench sections are collapsed, to cover the compartments of the table top sections, and braces detachably connecting between the latter sections, when used as seat or bench 95 sections, and the table top sections, said braces having means overlying the hinged joint of the table top sections, said seat or bench sections having cleats adjacent their opposite ends to overlie the ends of the 100 table top sections and to engage each other, said seat or bench sections having sheet metal marginal flanges overlapping each other and overlying the table top sections, thereby concealing the table top sections and 105 also rendering the device proof against foreign matter.

7. In a collapsible camping outfit, the combination with a pair of table top sections having compartments, means for hingedly 120 uniting said sections, whereby they may be folded with the compartments facing outwardly, of seat or bench sections having supporting legs, and adapted, when the seat or bench sections are collapsed, to cover the 125 compartments of the table top sections, and braces detachably connecting between the latter sections, when used as seat or bench sections, and the table top sections, said braces having means overlying the hinged 130

joint of the table top sections, said seat or bench sections having cleats adjacent their opposite end to overlie the ends of the table top sections and to engage each other, said seat or bench sections having sheet metal marginal flanges overlapping each other and overlying the table top sections, thereby concealing the table top sections and also

rendering the device proof against foreign matter, and means for holding the supporting legs either depending from the seat or bench sections or collapsed thereagainst. ¹⁰

In testimony whereof I hereunto affix my signature.

HENRY PUFF.
